UNITED STATES PATENT OFFICE.

GEORGE D. FOX, OF BUFFALO, NEW YORK.

DESIGN FOR A BROOM-HOLDER.

SPECIFICATION forming part of Design No. 31,591, dated October 3, 1899.

Application filed September 11, 1899. Serial No. 730,177. Term of patent 14 years.

To all whom it may concern:

Be it known that I, GEORGE D. FOX, a citizen of the United States, residing at Buffalo, in the county of Erie and State of New York, have invented and produced a new and original Design for a Broom-Holder, of which the following is a specification, reference being had to the accompanying drawing, forming a part thereof.

5 This design relates to the shape or configuration of a broom-holder.

The accompanying drawing is a perspective view of a broom-holder embodying my design.

5 The leading feature of my design consists of a pair of horizontal side bars or members projecting forwardly from a base-plate, a pair of jaws arranged lengthwise between said side bars and having their outer portions connected with the outer portions of said bars by curved bends, and a horizontal ring arranged at the inner ends of said jaws.

Referring to the drawing, A is the base-plate of the broom-holder, and a are openings in the upper and lower portions thereof.

5 B B are the horizontal side bars or members of the holder, which diverge forwardly from the base-plate.

C C are the jaws, which are arranged between the outer portions of the side bars B 30 and terminate at a distance from the front side of the base-plate A, and d d are the curved bends which connect the front portions of the jaws with the front portions of the side bars. The jaws C converge forwardly or toward the bends d, as shown.

F is the ring, arranged horizontally at the inner ends of the jaws C and occupying the space between the inner portions of the side bars B and between the front side of the 40 base-plate A and the inner portions of the jaws.

What I claim is—

The design for a broom-holder, substantially as herein shown and described. 45

Witness my hand this 21st day of August, 1899.

GEORGE D. FOX.
